DESIGN FOR A DECORATIVE ALPHABET
FOR FORMING MONOGRAMS FOR WEAR-
ING APPAREL OR SIMILAR ARTICLE

Charles Emmey, New York, N. Y.

Application November 4, 1935, Serial No. 59,382

Term of patent 14 years

To all whom it may concern:

Be it known that I, Charles Emmey, a citizen of the United States, residing in the city and county of New York, State of New York, have invented a new, original, and ornamental Design for a Decorative Alphabet for Forming Monograms for Wearing Apparel or Similar Article, of which the following is a specification, reference being had to the accompanying drawing, forming part thereof.

The letters forming the alphabet and as applied are of no appreciable thickness.

In the drawing:

The figure is a plan view of a decorative alphabet for forming monograms or the like for wearing apparel, forming the present design.

I claim:

The ornamental design for a decorative alphabet for forming monograms for wearing apparel or similar article, as shown and described.

CHAS. EMMEY.
